FRANK CONRAD, OF SWISSVALE, PENNSYLVANIA, ASSIGNOR TO WESTINGHOUSE ELECTRIC AND MANUFACTURING COMPANY, A CORPORATION OF PENNSYLVANIA.

ELECTRICAL SYSTEM.

1,191,158.

Specification of Letters Patent. Patented July 18, 1916.

Application filed September 4, 1913. Serial No. 788,088.

To all whom it may concern:

Be it known that I, FRANK CONRAD, a citizen of the United States, and a resident of Swissvale, in the county of Allegheny 5 and State of Pennsylvania, have invented a new and useful Improvement in Electrical Systems, of which the following is a specification.

My invention relates to electrical systems 10 of distribution, and it has special reference to a combination of a control system with a telephone system which utilizes certain of the control circuits.

The object of my invention is to provide 15 a combined electrical system of the above-indicated character which shall increase the safety and convenience of operation without the addition of any undue complications and expense in apparatus.

With this end in view, I install, at suitable points in a system of distribution, a plurality of telephone sets that are severally energized from the secondary windings of a plurality of transformers, the primary 25 windings of which are severally connected in certain of the control circuits. In this manner, I obtain the advantages of added safety and convenience without the expense of a separate transmission line.

The system of distribution which I will hereinafter describe is fully set forth in my co-pending application, Serial No. 659,185, filed November 8, 1911, although it will be understood that my invention is not limited 35 to any one particular system, but is capable of much wider application. The system in question embodies automatic means for eliminating one or more sections of a trolley circuit, under predetermined conditions, 40 such as the occurrence of grounds on said sections, and means for temporarily introducing resistance into the supply circuit of the system, not only while one or more defective sections are being excluded from circuit, but also during the time when the sections are being reinserted.

The single figure of the accompanying drawing is a diagrammatic view of an electrical system embodying my invention.

For convenience and clearness of illustration, I have shown a single distributing section and have otherwise simplified the diagram. It is understood, however, that I do not limit myself to any particular num-

ber of sections or to the arrangement of conductors included therein.

Referring to the drawing and considering first the system of distribution, energy may be supplied from any suitable grounded source (not shown) through a main feeder 60 conductor 1, and a tap 2, to a trolley conductor 3. Each trolley conductor is divided into a plurality of sections the ends of which are tied together by bus bars (not shown) and is provided with suitable circuit-interrupters 4.

The feeder circuit is provided with a main circuit interrupter 5 and a resistor 6 which is normally short-circuited by a switch or circuit-breaker 7. In addition to 70 the main feeder 1, I provide an auxiliary grounded feeder 8 and a pair of control conductors 9 and 10 which may both be supplied with energy from either the main feeder or the auxiliary feeder, or one may 75 be supplied from one feeder and one from the other, according to the positions occupied by double-throw switches 11 and 12.

Control stations are located between trolley sections and are provided with manually 80 operated control switches 13, 14 and 15.

The circuit-breakers 5 and 7 are located in the main generating or control station which is also equipped with relay switches 16, 17 and 18, a circuit-closing switch 19 for 85 the control conductors 9 and 10, and short-circuiting switches 20 and 21. Another pair of control conductors 22 and 23 are disposed adjacent to the conductors 9 and 10 and a plurality of telephone sets 24 are 90 tapered off at predetermined points from the conductors 22 and 23, which thus serve also as the telephone circuit conductors. The telephone sets 24 are, for safety, preferably severally connected to the line 95 through "repeating transformers" 25 and 25*, the mid-points of the secondary windings of which are severally grounded. As an additional safety precaution, suitable lightning arresters 26 and fuses 26* are provided.

The operation of, and the circuit connections for, my improved system are as follows: Assuming that the switching devices and circuit-breakers occupy the positions 105 shown in the drawing, the resistance section 6 being shunted, and the section circuit-breaker 4 being closed, if trolley conductor

- 3 is accidentally connected to ground, as indicated at 27, so that a short circuit occurs on the line, a heavy current will immediately be supplied from the feeders, 6 through interrupter 4 and the primary winding of series-transformer 28, to ground. Consequently, the amount of current traversing other circuit interrupters and series transformers in the vicinity may also be 10 considerably greater than the normal current supplied through them for operation. For this reason, if the circuit breakers for each section are properly set to protect the said section against grounds and other adverse conditions, not only the grounded section 15 3, but many other sections may obviously be excluded from the circuit. In the system illustrated, the first effect of a ground or other cause of abnormal demand, 20 on any section of the line, is to energize series-transformer 29 which is connected in the feeder circuit 1 adjacent to circuit-breaker 5 and which supplies current to magnet winding 30 of relay switch 47. 25 When relay switch 17 is actuated, a control circuit is established from any suitable source through conductor 31, contact terminals 32 of the relay switch and magnet winding 33 of relay switch 16 to conductor 34, which is connected to the opposite terminal of the source of supply. The relay switch 16, is raised in opposition to a dashpot 35, when its coil is energized, and, consequently, some time intervenes between the 35 completion of the circuit through its coil 33 and the closing of relay switch 16. In the meantime, energy is supplied through relay switch 17, conductor 36, contact terminals 37 of the relay switch 18, conductor 38, 40 trip coil 39 of the circuit-breaker 7 and auxiliary control contact terminals 40 of the same circuit breaker to line conductor 34. When coil 39 is energized, breaker 7 is immediately opened and resistor 6 is inserted in the feeder circuit 1. The consequent reduction of current in the feeder is sufficient to restore substantially normal conditions on all of the line circuit breakers, with the exception of circuit breaker 7 and 45 one other (not shown) that are located in the same section as the ground 27. When circuit-breaker 7 is opened, energy is supplied from control line conductor 34 through contact members 41, conductor 42 and closing coil 43 of switch 19, to opposite line conductor 34. As soon as switch 19 is closed, energy is supplied from feeder conductor 1, through switch 12, conductor 44 and switch 19 to control conductor 9. Inasmuch as the primary winding of transformer 45 is connected between control conductor 9 and the ground and the primary winding of transformer 46 is connected between control conductor 10 and the ground, 50 it is evident that transformer 45 is energized only when the resistor short-circuiting breaker 7 is open and switch 19 is closed, while transformer 46 is supplied with energy at all times. As soon as current is supplied to the conductor 9, the secondary 55 circuit of the transformer 45 is completed through conductor 47, switch 13, conductor 48, relay switch 49, which it will be understood has previously been closed by reason of the overload current through the secondary 60 circuit of the series transformer 28, and conductors 50 and 51 to the tripping coil 52 of the circuit-breaker 4. In a similar manner, a circuit-breaker (not shown) located at the other end of the section is opened, 65 thus excluding the grounded section from the circuit, and the action is usually complete before relay switch 16 has an opportunity to completely close. If, however, the trouble is so serious that the exclusion of the 70 grounded section does not remedy the abnormal condition, or the introduction of resistance does not produce sufficient reduction of the current, relay switch 16 may be closed, in which case, energy is supplied from conductor 31, through relay 16, conductor 53, the tripping coil 54 of the main circuit-interrupter 5, and conductor 55 to negative conductor 34. As soon as the circuit-breakers at the respective ends of the 75 grounded section are opened, the current traversing coil 30 of relay switch 17 will be so far reduced as to permit relay switch 17 to drop and establish a connection across contact terminals 56, thereby completing a 80 circuit from conductor 31, through conductor 57, contact terminals 58 of circuit-breaker 5, the closing coil 59 of the circuit-breaker 7 and auxiliary contact terminals 60 of the same circuit-breaker to conductor 34. As soon as the grounded section is excluded from the circuit, the resistor 6 is again short-circuited by the closing of circuit breaker 7. The 85 closing coil 43 of switch 19 is deenergized when circuit-breaker 7 is closed and switch 19 is opened by a spring 61, thereby deenergizing control conductor 9 and transformer 45. 90 Assuming that the ground 27 has been removed and the section 3 repaired, and that it is desired to reconnect the section into the system, this may be accomplished as follows: The control switch 15 is first thrown to position *a*, in which position a circuit is established from transformer 46, through conductor 62, switch 13, conductor 63, switch 14, conductor 64, contact terminals 65 of switch 15, conductor 66, and coil 67 of a relay switch 68, to ground. The relay switch 68, when energized, completes a circuit from one terminal of a storage battery 69, through coil 70 of relay switch 18, conductor 71, a portion of the primary winding 72 of the telephone "repeating transformer" 100 105 110 115 120 125 130

25, conductors 73, 22 and 74, a portion of the primary winding 75 of another "repeating transformer" 25^a that is located at any pre-determined distance from the transformer 5 25, conductor 76, contact members 77 of the previously closed relay switch 68, conductor 78, the remaining portion of the primary winding 75 of the transformer 25^a, conductors 79, 23 and 80, the remaining portion 10 of the primary winding 72 of the transformer 25, conductor 81 and a second coil 82 of relay switch 18 to the opposite terminal of the battery 69. When the coils 70 and 82 are energized relay switch 18 is 15 raised and bridges contact members 83, thereby completing a control circuit from conductor 31 through conductor 38 and trip coil 39 of the circuit-breaker 7, as hereinbefore explained. By this means, circuit- 20 breaker 7 is opened and the resistor 6 is temporarily inserted. As already pointed out, circuit-closing switch 19 will be closed as soon as circuit-breaker 7 is opened and, consequently, energy will be supplied from 25 feeder conductor 1, through switch 12, conductor 44 and switch 19 to control conductor 9. Transformer 45 will, consequently, be energized and current will be supplied from its secondary winding, through conductor 47, switch 13, conductor 84, switch 14, conductor 85, contact terminals 86 of switch 15, conductor 87, and closing coil 88 of circuit-breaker 4 to ground, thus closing the circuit breaker. The switch 15 is 30 provided with centering springs 89 and, consequently, the switch must be held manually in position *a* during the above-described cycle of operation, which, however, occupies a very short time. As soon as 35 manually-operated switch 15 is released, relay switch 68 is disengaged, relay coils 70 and 82 are deenergized and relay switch 18 is allowed to drop to its lower position across contact members 37. If normal 40 conditions obtain on the system, relay coil 30 is deenergized and relay switch 17 drops to bridge its terminals 56, thereby completing a circuit through closing coil 59 of circuit-breaker 7 and effecting the closure of 45 said breaker.

It thus appears that the trolley sections may be cut in or out, at the will of an attendant, by manipulating the proper switches at the several stations, while, at 55 the same time, the resistance is automatically inserted in the feeder circuit before a trolley section is automatically excluded and also, under normal conditions, before the circuit-breakers may be closed to 60 connect any of the sections. By reversing the positions of the switches 11, 12 and 13, closing the switch 21 and opening the switch 20, the control conductor 9 may be continuously energized, instead of the control conductor 10.

The construction and operation of the telephone sets 24 are deemed to be known well enough to obviate the necessity of any detailed description here. The system is preferably of the type that employs, as a 70 source of power, an induction coil that is energized by suitable batteries, which apparatus is preferably disposed in a casing 90. The function of the "repeating transformers" 25 and 25^a has already been pointed out. It will be noted that a condenser 91 is shunted across the contact terminals 77 of the relay switch 68, thereby at all times offering a path for the telephone current, although the circuit is open at the condenser to direct current from the battery 69. Also, condensers 92 are severally connected in parallel relation with the coils 70 and 82 of the relay switch 18. In this case, the condensers are used chiefly as protective apparatus for the coils, in order to eliminate or minimize the effect of the accumulation of static voltages. As protection against a similar contingency, the battery 69 is grounded at its mid-point. 90

It will be understood that variations in the arrangement of parts and circuit connections of the system may be effected within the spirit and scope of my invention; I, therefore, desire that only such limitations 95 shall be imposed as are indicated by the appended claims.

I claim as my invention:

1. The combination with a plurality of complete sets of message-communicating means, and a plurality of conductors for interconnecting said sets, of a control system normally embodying said conductors, a normally open switch for bridging said conductors, and an electrical condenser connected across said switch to permit of uninterrupted communication between said sets. 100

2. The combination with a plurality of complete telephone sets located at materially separated points, and a plurality of conductors for interconnecting said sets, of a control system normally embodying said conductors, a normally open switch for bridging said conductors, an electrical condenser connected across said switch to permit of uninterrupted telephonic communication, and a source of direct-current energy for intermittently energizing said conductors according to the position of said switch. 110

3. The combination with a plurality of complete telephone sets, and a plurality of conductors for interconnecting said sets, of a control system normally embodying said conductors, a source of direct-current energy 125 adapted to intermittently energize said conductors, and means for permitting the passage of telephonic current through said conductors irrespective of their energization from said source of energy. 130

4. The combination with a plurality of complete telephone sets, and a plurality of conductors for interconnecting said sets, of an electric distribution system comprising 5 main circuits and a plurality of auxiliary control circuits including said conductors, a normally open, electrically-controlled switch for bridging said conductors, the actuating coil of the switch being energized 10 from said distribution system, a source of direct-current energy adapted to intermittently energize said conductors according to the position of said switch, and means for permitting the passage of telephonic current 15 through said conductors irrespective of their energization from said source of energy.
5. The combination with a plurality of complete telephone sets, and a plurality of conductors for interconnecting said sets, of 20 an electric distribution system comprising main circuits and a plurality of auxiliary control circuits including said conductors, a normally open, electrically-controlled switch for bridging said conductors, the actuating coil of the switch being energized 25 from said distribution system, a source of direct-current energy adapted to intermittently energize said conductors according to the position of said switch, switching means 30 energized by the closure of said switch to effect predetermined circuit changes in said
- distribution system, and an electrical condenser connected across said switch to permit of telephonic communication between said sets through said conductors irrespective of their energization from said source of energy.
6. The combination with a plurality of complete telephone sets located at materially separated points, and a plurality of repeating transformers respectively having their secondary windings directly connected to said telephone sets, and a plurality of conductors for interconnecting said sets and including the primary windings of said 40 transformers, of an auxiliary control system including said conductors and primary windings, a normally open switch for bridging said conductors, an electrical condenser connected across said switch to permit of uninterrupted telephonic communication, and a source of direct-current energy for intermittently energizing said conductors according to the position of said switch.

In testimony whereof, I have hereunto subscribed my name this 2nd day of September, 1913.

FRANK CONRAD.
